UNITED STATES PATENT OFFICE.

ROBERT JARDINE, OF DETROIT, MICHIGAN, ASSIGNOR TO RICH TOOL COMPANY, OF DETROIT, MICHIGAN, A CORPORATION OF MAINE.

TAPPET AND METHOD OF MAKING SAME.

Application filed January 5, 1926. Serial No. 79,361.

In the drawings:

Figure 1 is an elevational view, partially in section, of a wearing disk and the body portion of a tappet before forging them together;

Fig. 2 is an elevational view, partially in section, of the body portion of the tappet shown in Fig. 1;

Fig. 3 is a sectional elevational view of a wearing disk;

Fig. 4 is a bottom plan view of the disk shown in Fig. 3;

Fig. 5 is a sectional view of the tongue and slot connections between the wearing disk and the body portion of the tappet before forging such connections;

Fig. 6 is a sectional view similar to Fig. 5 and after forging the connections;

Fig. 7 is a sectional elevational view of a modified tappet before forging the body portion of the tappet to the wearing disk;

Fig. 8 is a sectional view similar to Fig. 7 and after forging the body portion of the tappet to the wearing disk;

Fig. 9 is a sectional elevational view of a modified form of the body portion of a tappet; and

Fig. 10 is a sectional elevational view of the tappet body shown in Fig. 9 forged in locking engagement with a wearing disk.

This invention relates to tappets which are operated by a cam shaft in an internal combustion engine to control the valves thereof, and it is an object of the invention to provide a tappet having a wearing disk of material adapted to be hardened and a body portion of a different type of metal. It is also an object of the invention to provide a tappet with a wearing disk composed of metal adapted to be hardened and having a forged dove-tail connection with the body portion of the tappet.

Referring to Figs. 1 to 6, inclusive, of the drawing, a tappet 1 is illustrated comprising a body portion 2 and a wearing disk 3. The body portion 2, which comprises a stem 4 and head 5, is composed of material which is easily machined. The wearing disk 3, however, is composed of material which may be hardened to withstand the wearing action of the cam in an internal combustion engine. The disk 3 may be composed of metal which may be forged such, for example, as the so-called high speed steel or tung-

sten steel or may be composed of metal which is not adapted to be forged such, for example, as chilled white iron or unannealed malleable iron.

The disk 3 and the body portion of the tappet are preferably connected together by forged (upset) tongue and slot connections. Referring to Fig. 2, it should be noted the head 5 has a plurality of circular grooves 6 formed therein and an outside shoulder portion 7. The disk 3, as shown in Fig. 3, is provided with a plurality of circular grooves 8 which are adapted to fit the tongues or ridges forming the grooves 6 in the head 5 of the tappet body. The disk 3 is positioned in the top of the head 5 prior to a forging operation with the grooves 8 in the disk 3 and the ridges forming the grooves 6 in the head 5 in the position shown in Fig. 5 and also in Fig. 1 in the drawing. At this time the tongue and slot connections are not so locked as to insure against separation of the disk from the tappet body. Prior to the mounting of the disk in the head either the head is heated or the head and disk are heated for a forging operation. If the disk 3 is composed of material adapted to be forged, such as tungsten steel, then the head and disk are both heated.

The forging of the tongue and slot connections forces them to take a dove-tail shape such as shown in Fig. 6 of the drawing. Such dove-tail connections insure against any movement of the wearing disk in the head of the tappet and, moreover, insure against the falling out of portions of the disk in case it is cracked or broken. During the forging operation the shoulder 7 on the head 5 is pressed firmly into engagement with the disk 3. As above set forth, the disk 3 may be connected to the body portion of the tappet when in a heated or in a cool condition. In case the disk 3 is in a cool condition, pronounced dove-tail shape ridges may not be formed in that part of the tongue and slot connections which are a part of the disk 3. In such case wedge shaped grooves may be formed in the disk before it is forged if so desired.

Figs. 7 and 8 illustrate a modification of the invention wherein the body portion of the tappet is lightened and reduced somewhat in weight. The body portion of the tappet comprises a stem 10 having an open-

ing 11 in the center thereof and a head 12 which is preferably formed as an integral part of the stem 10. The head 12 is cup-shaped and is not provided with a plurality of circular grooves as the head 5 shown in Figs. 1 and 2. A disk 13, which is adapted to fit in the head 12 as shown in Fig. 7 of the drawing, is provided with a wedge-shaped projection 14 on the bottom thereof. The 10 disk 13 is provided with a tapered side 15 adapted to be engaged by the shoulder 25 on the head 12. The tapered side 15 and the wedge-shaped projection 14 serve to effect dove-tail connection between the disk and 15 the body portion of the tappet after a forging operation. The disk 13 may be formed as a casting or may be made of metal adapted to be forged.

After assembling the disk 13 with the body 20 portion of the tappet, the body portion is upset and forged for securely fitting around the wearing disk 13 to form tongue and slot connection as shown in Fig. 8 of the drawing. The metal forming the head of the 25 body portion is upset to engage the projection 14 and to securely fit the side 15 of the disk. Suitable threads 16 may be formed in the end of the body portion for connection to a tappet rod.

30 In the modification shown in Figs. 9 and 10 of the drawing, the body portion 17 comprises a straight tube 18 having threads 19 cut in the lower end thereof. The wearing disk 20 is enlarged somewhat with respect 35 to the wearing disk shown in Figs. 1 and 8 of the drawing and has one circular groove 21 formed therein for attaching it to the body portion of the tappet. The groove 21 may be tapered or wedge-shaped, as indicated 40 in Fig. 10 of the drawing, or may be formed with sides perpendicular to the wearing surface of the disk. Such disk may be made of cast material which is adapted to be forged or may be made of metal such as tungsten 45 steel which is suitable for a forging operation. In case the disk is made of forgible material it is not necessary to form the groove 21 wedge-shaped. However, if the disk 20 is composed of cast material, it is desirable 50 to form the groove 21 wedge-shaped. The body portion of the tappet is forged into engagement with the disk 20 as shown in Fig. 10 of the drawing. The metal forming the body portion of the tappet is upset and 55 squeezed securely into the groove 21.

What is claimed is:

1. A tappet comprising a disk composed of material adapted to be hardened for withstand wear, and a body upset into interlocking engagement with a portion of said disk.
2. A tappet comprising a head and a body portion composed of material adapted to be forged, and a disk composed of a material 65 adapted to be hardened to withstand wear,

said disk having an upset dove-tail forged connection with said head.

3. A tappet comprising a body portion composed of one type of metal, a disk composed of a different type of metal adapted to 70 be hardened to withstand wear, and a plurality of forged tongue and slot connections between the body portion and the disk.

4. A tappet comprising a body portion having a plurality of grooves therein, and a 75 disk composed of material adapted to be hardened to insure against wear and having grooves therein interlocked with the before-mentioned grooves, said interlocking being effected by a forging operation. 80

5. A tappet comprising a stem and a head of one type of metal and a disk formed of a metal different from the metal forming the stem and head, said disk having a forged 85 annular tongue and slot locking engagement with said head.

6. A tappet comprising a stem having a head thereon, said head having a plurality of grooves formed therein and composed of material adapted to be forged, and a disk 90 having grooves therein interlocked with the grooves in the head by a forging operation, said disk being composed of material adapted to be hardened to withstand wear.

7. A method of forming a tappet which 95 consists in shaping a body portion and a wearing disk to have tongue and slot connection with each other, and in upsetting the connection to form dove-tail engagement between the disk and the body portion of the 100 tappet.

8. A method of forming a tappet which consists in shaping a body portion and a wearing disk to have a tongue and slot connection with each other, and in upsetting the 105 body portion while in engagement with the disk to form a fixed connection between the disk and the body portion.

9. A method of forming a tappet which consists in forming a head on a stem with a 110 plurality of grooves therein, in forming a plurality of grooves in a disk of material adapted to be hardened, in mounting said disk on the head with the grooves in the head and disk intermeshing, and in forging said head and disk in engagement with each other to form a dove-tail connection between them. 115

10. A method of forming a tappet which consists in shaping a body member and a wearing member to have a tongue and groove 120 connection with each other, and in concurrently so forging the connecting portions of both said members that the tongue on one member is securely embedded in the metal of the other member, said tongue being so 125 shaped as to insure a locking engagement between the members.

In witness whereof I have hereunto set my hand.

ROBERT JARDINE.
